UNITED STATES PATENT OFFICE

169,125

CUTOUT TOY

Theresa C. Cheresh, Chicago, Ill.

Application October 31, 1951, Serial No. 17,194

Term of patent 7 years

(Cl. D34—15)

To all whom it may concern:

Be it known that I, Theresa C. Cheresh, a citizen of the United States, residing at Chicago, in the county of Cook and State of Illinois, have invented a new, original, and ornamental Design for a Cutout Toy, of which the following is a specification, reference being had to the accompanying drawings, forming a part thereof.

Fig. 1 is a front elevational view of a cutout toy, showing my new design;

Fig. 2 is a top plan view thereof;

Fig. 3 is a perspective view thereof showing the elements in a slightly different position; and

Fig. 4 is a top plan view of the article as shown in Fig. 3.

I claim:

The ornamental design for a cutout toy, substantially as shown.

THERESA C. CHERESH.
